CLAIM

The ornamental design for a pin for IC testing device as shown and described.

DESCRIPTION

FIG. 1 is a top front right side perspective view of a pin for IC testing device showing my new design;

FIG. 2 is a top rear left side perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.
